UNITED STATES PATENT OFFICE.

SAMUEL H. TINSMAN, OF MORRIS, ILLINOIS, ASSIGNOR TO PERU PLOW & WHEEL COMPANY, OF PERU, ILLINOIS.

PLANTING-MACHINE.

SPECIFICATION forming part of Letters Patent No. 764,509, dated July 5, 1904.

Application filed September 12, 1903. Serial No. 172,882. (No model.)

To all whom it may concern:

Be it known that I, SAMUEL H. TINSMAN, a citizen of the United States of America, and a resident of Morris, Grundy county, Illinois, 5 have invented a certain new and useful Improvement in Planting-Machines, of which the following is a specification.

My invention relates to corn-planters in general, but more particularly to corn-planters 10 of that construction in which the seeding mechanism is capable of a check-row mode of operation, and more particularly to that type of check-rower in which the dropping mechanism is adapted to be operated by check-row 15 wires.

Generally stated, the object of my invention is the provision of an improved and highly-efficient corn-planter.

A special object is the provision of an improved construction and arrangement for permitting the runners to be raised and lowered at will.

Another object is the provision of an improved swinging connection between the runner-frame and the wheels.

It is also an object to provide certain details and features of improvement tending to increase the general efficiency and serviceability of a corn-planter of this particular character.

To the foregoing and other useful ends my invention consists in matters hereinafter set forth and claimed.

In the accompanying drawings, Figure 1 is a plan of a corn-planter embodying the principles of my invention. Fig. 2 is a longitudinal section on line 2 2 in Fig. 1. Fig. 3 is an enlarged detail of the connection between the tongue and the rock-shaft, which constitutes a part of the means for raising and lowering the runners. Fig. 4 is a view similar to Fig. 2, but showing the runners lifted from the ground. Fig. 5 is an enlarged detail of the connection between the tongue and the rear axle.

As thus illustrated my improved corn-planter comprises an axle A, supported by wheels B B. It also comprises a tongue C, extending rearwardly and connected with the

center or middle portion of the axle A. The means for connecting the rear end of the 50 tongue with said axle may be of any suitable known or approved character—as, for example, the clip a. (Shown in Fig. 5.) With respect to the rocking or oscillating action of this axle (to be hereinafter described) the central portion of the polygonal axle can be round or cylindric, so as to turn readily in the said clip. The said tongue can be also connected to said axle by means of rearwardly-extending bars c, which latter are secured to the tongue 55 at c' and adapted to engage or connect with the axle at c². The construction is, of course, such that the said axle can turn relatively to said bearing portions c². These bars c may have rear extensions c³, adapted to support a 60 rotary scraper-bar c⁴, provided at each end with the scrapers c⁵. A foot-lever D can be employed for rotating this scraper-bar c⁴, and thereby applying the scrapers to the channeled peripheries of the wheels B. 65

It will be seen that the forward portion of my improved corn-planter is of an exceedingly light and at the same time strong and rigid construction, the runner-frame involving merely the usual rock-shaft E for operating the dropping mechanism and also a bail F, the latter constituting a part of the means for raising and lowering the runners or furrow-openers G. It will be understood that the seedboxes H and the dropping mechanism 70 can be of any suitable known or approved construction. The guide-rolls h, also the notched arms h' on the ends of the rock-shaft E, can also be of any desired form or construction consistent with their function of guiding 75 the check-row wires and engaging the knots or enlargements on the latter for the purpose of intermittently operating the dropping mechanism.

The bail-shaft F is preferably mounted to 80 turn in bearings f, secured to the bars c, and is provided at its ends with crank-arms f', adapted to engage the forward ends of the said runners. The means for rocking this bail F and also for rocking or oscillating the 85 axle A comprises an arm f² on the bail F, an

arm a' on the said axle, a link I, connecting said arms, and another link i, connecting the arm a' with an operating-lever J. This operating-lever is preferably pivoted at its lower 5 end to the tongue and is provided with the usual hand-operated dog or locking device adapted to engage the rack j, which latter is rigidly secured to the said tongue.

It will be observed that the runners are 10 practically independent of each other as far as any rigid connecting - framework is concerned and that the top of each runner has a framework of its own. Each runner-frame is preferably provided with rearwardly-extending ears g. These ears are connected with the axle A by means of arms g'. These arms are rigidly secured to said axle, but are provided with forward portions g'', adapted to rotate in the said ears or bearing portions 20 g. Thus it will be seen that the axle A, the bail F, and the rock-shaft E constitute the sole medium of connection between the two runners. Thus constructed my improved corn-planter is light and strong and rigid, and, 25 furthermore, is comparatively inexpensive to manufacture.

It will be seen that the tongue extends rearwardly and is connected directly with the axle. With this arrangement the runners 30 can be raised and lowered at will without raising and lowering the tongue. In other words, the runners are raised and lowered relatively to the tongue and rear wheels, thus rendering the machine exceedingly easy to 35 manipulate and handle. When the runners are down, the hand-lever and link connections, the axle, rock-shafts, and crank-arms are in the position shown in Fig. 2. The runners are raised by grasping the lever J and pulling 40 it rearward, so as to not only rotate the bail F, but also the axle A. The said axle and forward rock-shaft are thus practically simultaneously rocked for the purpose of raising the runners from the ground. The arms 45 g' on the axle lift the heels or rear portions of the runners, while the arms f' on the rock-shaft F simultaneously therewith lift the forward portions of the runners. In this way, as stated, the runner-framework involves but 50 few parts, is light and strong and rigid, and is raised and lowered at will without the necessity of lifting and lowering the tongue.

I claim as my invention—

1. A planting-machine, comprising a rocking axle, wheels on said axle, a tongue connected directly with the said axle, runners carrying suitable hoppers and dropping mechanism and adjustable relatively to said tongue, and means including said axle for raising and 55 lowering the said runners.

2. A planting-machine comprising a pair of wheels, a rocking axle supported by said wheels, a tongue suitably connected with said axle, a pair of runners carrying suitable hop-

pers and dropping mechanism and adjustable 65 relatively to said tongue, and means including said axle and a hand-lever suitably connected for raising and lowering said runners.

3. A planting-machine comprising a pair of runners carrying suitable hoppers and dropping mechanism, an axle constituting the sole medium of connection between the rear portions of said runners, a rock-shaft for operating the said dropping mechanism, a bail constituting the sole medium of connection between the forward ends of said runners, a tongue rotatively connected with both the said axle and the said bail, and a lever suitably connected for simultaneously rocking said axle and bail and thereby raising and lowering 80 said runners.

4. A planting-machine comprising a pair of wheels, a rocking axle supported by said wheels, a pair of runners carrying suitable hoppers and dropping mechanism, and means 85 including said axle for raising and lowering said runners.

5. A planting-machine comprising an axle, wheels on said axle, a bail connecting the forward ends of said runners, and means including 90 said axle and bail for raising and lowering said runners.

6. A planting-machine comprising a pair of wheels, an axle supported by said wheels, a pair of runners arranged in front of said 95 wheels and carrying suitable hoppers and dropping mechanism, crank-arms connecting said axle with the rear portions of said runners, a tongue connected directly with said axle, and means including said axle and arms 100 for raising and lowering said runners, the said axle and crank-arms constituting the sole medium of connection between the upper rear end portions of said runners.

7. A planting-machine comprising runners, 105 a suitable tongue, suitable dropping mechanism and hoppers mounted on said runners, a pair of wheels traveling behind said runners, a straight axle supported by said wheels, arms rigidly secured to said axle and having forward portions rotatively connected with the upper rear end portions of said runners, and means including said axle and arms and a lever for raising and lowering said runners.

8. A planting-machine comprising runners 115 carrying suitable hoppers and dropping mechanism, a pair of wheels, a rocking axle supported by said wheels, a tongue having its rear end mounted on said axle, and means including said axle and a plurality of links 120 and crank-arms for raising and lowering said runners.

9. A planting-machine comprising a tongue, an axle having a rocking connection with said tongue, wheels on said axle, runners carrying 125 seedboxes and adjustable relatively to the tongue, and manually-controlled means suitably connected for rocking said axle and there-

by raising and lowering said runners and seed-boxes.

10. A planting-machine comprising a rocking axle, wheels on said axle, runners carrying seedboxes, and manually-controlled means suitably connected for rocking said axle and thereby raising and lowering said runners and seedboxes.

11. A planting-machine comprising supporting-wheels, a tongue, runners carrying seedboxes and adjustable relatively to said tongue, a rock-shaft carried by the tongue

and provided with arms connected with said runners, and manually-controlled means suitably connected for rocking said shaft and thereby raising and lowering said runners and seedboxes.

Signed by me at Morris, Grundy county, Illinois, this 27th day of August, 1903.

SAMUEL H. TINSMAN.
